[57] CLAIM

The ornamental design for a printer cartridge plate, as shown and described.

DESCRIPTION

FIG. 1 is a rear elevational view of a “printer cartridge plate” showing my design, the front view being a mirror image thereof;

FIG. 2 is a top rear perspective view thereof;

FIG. 3 is a bottom rear perspective view thereof;

FIG. 4 is a right side elevational view thereof; and,

FIG. 5 is a left side elevational view thereof.

The broken line depiction of a printer cartridge in FIGS. 1-5 is for illustrative purposes only, and forms no part of the claimed design.
